SLIDABLE LAMP SUPPORT

Filed July 25, 1947

UNITED STATES PATENT OFFICE

2,562,979

SLIDABLE LAMP SUPPORT

Clinton R. Yingling, Denver, Colo.

Application July 25, 1947, Serial No. 763,469

5 Claims. (Cl. 191—22)

1

This invention relates to an improved electric lamp support for supporting an electric lamp slidably on a desk or the like having a slideable contact for the circuit-connecting means so that the necessity of lengths of wire on the desk may be dispensed with.

It is an object of this invention to provide an electric lamp support of the kind to be more particularly described hereinafter in which elongated circuit contact members are carried by the support and slideable brushes or contact members are carried by the lamp so as to permit the lamp to be moved along the length of the support with the sliding contact members continuously engaged with the fixed contact members, eliminating wires extending from the lamp directly, which frequently obstruct a desk and continuously hinder the free movement of the lamp.

Another object of this invention is to provide a lamp of this kind having an extensible support and extensible circuit-connecting means carried by the support so that the support may be adjusted to any length desired for any particular desk or fixed support.

A further object of this invention is to provide a lamp support of this kind which may be used over bins in hardware stores or the like having bins where a slidably-mounted light would prove desirable.

With the foregoing objects in view, and others which may hereinafter more fully appear, the invention consists of the novel construction, combination and arrangement of parts as will be more specifically described, and illustrated in the accompanying drawings, wherein are shown embodiments of this invention, but it is understood that changes, variations and modifications may be resorted to which fall within the scope of the invention as claimed.

In the drawings:

Figure 1 is a front elevation, partly broken away, of an electric lamp support constructed according to an embodiment of my invention.

Figure 2 is a transverse section.

Figure 3 is a rear elevation, partly broken away and partly in section, of the horizontal extensible support;

Figure 4 is a fragmentary section, partly broken away, showing the sliding contact members;

Figure 5 is a fragmentary horizontal section taken on the line 5—5 of Figure 4; and

Figure 6 is a fragmentary rear elevation, partly broken away.

Referring to the drawings, the numeral 10 designates generally an electric lamp support com-

2

prising a fixed rail 11, a carriage 12 slidable on the rail, and a lamp 14 supported on the carriage 12.

The rail 11 is formed of a pair of telescoping rods 15 and 16 which are adapted to be fixedly mounted on a desk or fixed supporting structure. The rod 15 is slidably engaged in the rod 16 through one end thereof and the rods are bent at their free or outer ends rearwardly, as at 17, and 18. Attaching plates 19 are fixed on the terminal ends of the portions 17 and 18 for securing the ends of the rail to the desk so the length of the rail will be spaced from the desk. The rail 11 is formed of metal or plastic or other suitable material.

The rods or tubes 15 and 16 are formed with an elongated slot 20 along the length thereof on the inner side or side toward the supporting members 19 and the desk. A plug 21 is carried by one end of one of the bars, as at 17, and is formed with a pair of contacts 22 and 24 with which the contacts of a correlated plug 25 are adapted to be engaged. The plug 25 is carried by one end of an electric cord 26 which is adapted to be connected to a source of electric current to provide a supply circuit for the lamp 14. A pair of elongated resilient coil springs 27 and 28 are carried within the rail 11. The springs are provided to form continuous extensible contact members in the rail 11 and are adapted to be expanded when the bars 15 and 16 are extended and contracted when the rail is shortened. The ends of the springs 27 are fixed to hooks or eyes 29 carried by the opposite ends of the rail forming members 15 and 16. The eyes 29 at one end are connected to the terminals 22 and 24 of the plug 21, and the eyes 29 at the other end are fixed to an insulating plate 30 carried by the bar or tube 15 to insulate the springs from each other and from the rail 11. The springs are disposed adjacent the opening 20 in the members 15 and 16 so that they may be contacted by a sliding contact from without the rail 11.

The lamp-supporting carriage 12 is slidably mounted on the rail 11 for movement along the length thereof. The carriage 12 is formed of a flat plate 31 disposed on the inner side of the rail 11 and extending above and below the rail. A pair of rollers 32 are rotatably supported from the upper end of the plate 31 for engagement with the rail 11. Each of the rollers 32 is rotatably mounted between the ears 34 of an inverted U-shaped bracket 35 fixed to the upper end of the plate 31. The rollers 32 are provided for engaging the upper side of the rail 11.

The lower end of the plate 31 is bent outwardly and upwardly to form a U-shaped housing 36 closed at both ends. A spring-pressed roller truck 37 is mounted in the housing 36. The truck 37 is formed of an elongated body 38 which extends substantially the length of the housing 36 therein and is free for vertical movement. Arms 39 extend through openings 40 in the ends of the housing 36 for limiting the upward movement of the truck 37. A flat leaf spring 41 is engaged between the truck 37 and the lower wall or bottom 42 of the housing 36 for constantly urging the truck upwardly. Rollers 44 are rotatably carried by the truck 37 between upwardly-extending arms or ears 45. The rollers 44 are biased toward engagement with the lower edge 15 of the rail 11 for supporting the carriage 12 thereon for sliding engagement.

A tube 46 extending vertically is fixed on the rear or inner side of the plate 31. The tube 46 and plate 31 are formed with a small opening 47 therethrough adjacent the slot 20 of the rail 11. A vertically-extending shaft 48 is frictionally engaged through the tube 46 for sliding vertical adjustment therein, and an electric lamp 49 is fixed on the upper end thereof. The hollow shaft 48 is formed with an elongated slot 50 therein communicating with the aperture 47 of the tube 46 and plate 31. Electric wires 52 extending from the lamp 49 in the shaft 48 engage through the slot 50 and opening 47 so the shaft may be adjusted vertically while maintaining a circuit connection to the lamp 49.

A contact plug 54 is carried by the outer side of the plate 31 immediately adjacent the rail 11 and slot 20 therein. The plug 54 is made of suitable insulating material and a pair of contact members 55 and 56 are contained therein. The wires 52 are adapted to be connected to the contacts 55 and 56 in the plug 54 and a pair of brushes 57 or sliding contacts extend from the plug 54 through the opening 20 of the rail 11 for sliding engagement therewith.

In the use and operation of this lamp support, the rail 11 may be extended or contracted to suit the length of the desk or particular mounting. The extensible springs 21 and 23 are extended and contracted in accordance with the rail. While the carriage 12 is rollably or slidably mounted on the rail 11, the brushes 57 or sliding contact members maintain a circuit connection to the lamp 49 from the circuit leads 27 and 28 in all positions of the carriage on the rail. While the lamp 49 may be moved along the length of the rail 11 for horizontal adjustment, it may also be adjusted vertically by the shaft 48 slidably engaged in the sleeve or tube 46.

Having thus described my invention, what I claim is:

1. An electric lamp support comprising a pair of telescoping horizontal tubular rods, said rods formed with elongated slots in one side thereof, a pair of resilient conducting members in said rods adjacent said slots, a connecting plug at one end of one of said rods, said conducting member engaging the terminals of said plug, a lamp-supporting carriage, rollers on said carriage engaging said rods for sliding movement thereon,

a vertical lamp-supporting tube slidably carried by said carriage, an electric lamp on said latter tube, and circuit-connecting means in said latter tube and said carriage engaging said resilient conducting members for conducting current to said lamp.

2. An electric lamp support comprising a pair of telescopically related horizontal supporting rods, means securing said rods on a fixed support in spaced relation thereto, extensible circuit-connecting means carried by said horizontal rods, a lamp-supporting carriage slidably mounted on said horizontal rods, a vertical lamp-supporting shaft slidably mounted on said carriage, an electric lamp on said shaft, and circuit-connecting means in said carriage and said shaft slidably engaging said extensible circuit-connecting means for connecting said lamp to a source of current supply.

3. An electric lamp support comprising an elongated horizontally extensible rail member, a pair of horizontally extensible circuit-connecting means carried by said rail member, said means terminating in a plug on said rail for connection to a source of current supply, a lamp-supporting carriage, rollers on said carriage engageable with said rail, a vertical lamp-supporting shaft slidably mounted on said carriage, an electric lamp on said shaft, circuit-connecting means carried by said carriage and said shaft slidably engaging said extensible circuit-connecting means for connecting said lamp with said source of electric supply, said extensible circuit-connecting means including coil spring members.

4. An electric lamp support comprising an elongated horizontally extensible rail member, a pair of horizontally extensible circuit-connecting means carried by said rail member, said means terminating in a plug on said rail for connection to a source of current supply, a lamp-supporting carriage, spring-pressed rollers on said carriage engageable with said rail, a vertical lamp-supporting shaft on said carriage, an electric lamp on said shaft, and circuit-connecting means carried by said carriage and said shaft slidably engaging said extensible circuit-connecting means for connecting said lamp with said source of electric supply.

5. An electric lamp support comprising a pair of telescopically-engaged supporting members, supporting means for said members, extensible circuit-connecting means carried by said members, a carriage slidably engaged on said members for movement along the length thereof, an electric lamp on said carriage, and circuit-connecting means connected to said lamp and slidably engaging said extensible circuit-connecting means.

CLINTON R. YINGLING.
